UNITED STATES PATENT OFFICE.

GERALD C. WATERHOUSE, OF PASADENA, CALIFORNIA.

DESIGN FOR A TRAFFIC SIGNAL.

Application filed December 27, 1927. Serial No. 24,667. Term of patent 3½ years.

To all whom it may concern:

Be it known that I, GERALD C. WATERHOUSE, a citizen of the United States, residing at Pasadena, in the county of Los Angeles, State of California, have invented a new, original, and ornamental Design for Traffic Signals, of which the following is a specification, reference being had to the accompanying drawing, forming a part thereof.

In the drawing, Fig. 1 is a front elevation showing a traffic signal embodying my new design, and Fig. 2 is a side elevation of the top portion thereof, the standard being shown broken away.

I claim:

The ornamental design for a traffic signal as shown.

GERALD C. WATERHOUSE.
